UNITED STATES PATENT OFFICE.

WILLIAM C. HAMNER, OF MORGANFIELD, KENTUCKY.

FARM-GATE.

SPECIFICATION forming part of Letters Patent No. 338,062, dated March 16, 1886.

Application filed August 28, 1885. Serial No. 175,564. (Model.)

To all whom it may concern:

Be it known that I, WILLIAM C. HAMNER, of Morganfield, in the county of Union and State of Kentucky, have invented a new and Improved Farm-Gate, of which the following is a full, clear, and exact description.

The object of my invention is to provide a new and improved farm-gate, which can be opened and closed some distance from either side of the gate by a pedestrian or a person in a vehicle or on horseback, and which gate is locked and unlocked automatically.

The invention consists in the construction and combination of parts and details, as will be fully set forth and described hereinafter, and pointed out in the claims.

Reference is to be had to the accompanying drawings, forming part of this specification, in which similar letters of reference indicate corresponding parts in all the figures.

Figure 1 is a side view of my improved gate. Fig. 2 is a sectional plan view of the same. Fig. 3 is an enlarged detail view of the locking device.

25 The gate A is hung on a post, B, and its free end swings against a post, C. The top rail, D, projects beyond the hinged end of the gate, and on the projecting end of the said top rail a lever, G, is pivoted, the inner end of which is connected by a rod or wire, F, with the upper end of a lever, E, pivoted on the gate, and passing through a notch, D', in one side edge of the top rail, D.

35 The sliding bolt H, passed through the swinging end part of the gate, is pivoted to the lever E, and is acted upon by a spring-rod, J, secured to the gate and bolt, and pressing the bolt in the direction of the swinging end of the gate.

40 On a cross-bar, K, on the inner side of the post C, two latches, L, are pivoted at the outer ends of said cross-bar, and the latches are provided at their inner ends with notches M. The upper prongs, M', of the latches rest 45 on pins N, projecting from the inner side of the post C.

Some distance from each side of the gate a post, O, is erected, against which the free end of the gate can swing, the said posts having 50 stop-boards Q', against which the end of the gate can rest.

On the upper end of each post O an arm, P, is secured, having eyes Q, through which the ropes R are passed, which have rings or handles S on the outer ends, and their inner ends 55 are connected with the outer end of the lever G.

The operation is as follows: When the gate is closed, the end of the bolt H is between the lower prongs, M', of the latches L. To open the gate either handle S is drawn down, whereby the lever G is swung in such a manner as to swing the upper end of the lever E in the direction toward the hinged end of the gate, thus disengaging the bolt from the latches. When the lever E rests against one end of the 65 notch D', the said lever E cannot be swung farther, and by continued drawing of the handle S the gate is swung in the direction from the person and against the post O, opposite the one at which the handle is being pulled. 70 The person can pass the gate, and after having passed, the other handle S is drawn and the gate swung against the post C. The end of the bolt H striking the bottom of a latch, L, raises it, and after the bolt H has passed the inner end of the latch it drops, and the bolt is thus held between the inner ends of the latches and is locked automatically. The pins N prevent the latches L from dropping too far. 75

By pivoting the arms P so that they extend 80 out over the road, the handles S are brought within easy reach of a driver, who can operate the gate-opening mechanism without leaving his seat. The arm P can easily be pushed back when loads of hay, straw, &c., pass 85 through the gate, so that the full width of the road may be had. If the arms extended into the road and were not pivoted, travel would be interfered with, and the said arms would be broken off. 90

I am aware that a gate has had a bar extending from its rear end, on which were levers connecting the same with the gate-latch, the posts at opposite sides of the gate having pivoted levers provided with ropes for operating 95 the gate and its latch; and I do not claim the same as of my invention.

Having thus described my invention, I claim as new and desire to secure by Letters Patent—

1. The combination, with the gate hinged to a post, B, the top rail of the gate extending over the top of said post, the latch H, the ver-

tical lever E, the horizontal lever G, pivoted on the extension of the top rail, the rod F, connecting the lever E with the inner end of the horizontal lever G, and the posts O O at 5 opposite sides of the post B, of the arms P, pivoted to the posts at their inner ends, the guides Q on said arms, and the cords R, connected to the outer end of the horizontal lever and extending through the guides on the arms P P, 10 substantially as set forth.

2. The combination, with a gate, its latch,

and a lever for operating the latch, of the side posts, O O, the arms P, pivoted at their inner ends to said posts, the guides Q on the arms, and the cords R, said cords being connected 15 with the gate-latch-operating lever and extending longitudinally over the arms P and through the guides Q, substantially as set forth.

WILLIAM C. HAMNER.
